(57) **CLAIM**

(22) Filed: **Mar. 29, 2018**

The ornamental design for an adjustable beverage container sleeve, as shown and described.

(51) LOC (12) Cl. **07-06**

DESCRIPTION

(52) U.S. Cl.

USPC **D7/619.1**

(58) **Field of Classification Search**

FIG. 1 is a perspective view of an adjustable beverage container sleeve showing my new design;

USPC D7/619.1–625, 605–608; D9/444
CPC B65D 81/3879; B65D 81/3874; B65D
81/3897; B65D 81/3876; B65D 2313/02;
A41D 13/0015; A41D 20/005; A47G
23/0216

FIG. 2 is a front view thereof;

See application file for complete search history.

FIG. 3 is a rear view thereof;
